UNITED STATES PATENT OFFICE

FRANK C. DELI, OF CHICAGO, ILLINOIS

DESIGN FOR A PENCIL

Application filed June 23, 1930. Serial No. 36,128. Term of patent 14 years.

To all whom it may concern:

Be it known that I, FRANK C. DELI, a citizen of the United States, residing at Chicago, in the county of Cook, Illinois, have invented a new, original, and ornamental Design for a Pencil, of which the following is a specification, reference being had to the accompanying drawing, forming part thereof.

Fig. 1 is a side elevational view of a pencil showing my new design; and

Fig. 2 is a top plan view of the same.

I claim:

The ornamental design for a pencil as shown.

FRANK C. DELI.
